PORTABLE JIB CRANE

Filed March 24, 1932

UNITED STATES PATENT OFFICE

2,015,604

PORTABLE JIB CRANE

Mario Molinelli, Milan, Italy

Application March 24, 1932, Serial No. 601,013
In Italy March 27, 1931

11 Claims. (Cl. 212—49)

The invention relates to portable cranes such as are used for emergency jobs, as for rescuing trains, motor cars, boats and the like, or for building roads, railways and other buildings for which it is not convenient to assemble a stationary crane, whilst one must hoist very heavy loads, as are posts of telephonic or electric lines, feeders, etc.

The scope of the invention is to provide an automatic control, adapted to quickly and surely displace the counterweight, so that the counterbalance be assured with any position of the jib and any load on the hook, comprised inside of the capacity of the crane.

15 Cranes are already known with automatic displacement of counterweight in accordance either with displacement of the load or with luffing of the jib or with increase of the load. With these cranes it is not possible to carry out a perfect 20 balancing of load. Cranes are also known, wherein the counterweight is driven by an electric motor, which, however, is controlled by hand. Thus, it is possible, in theory, to keep a constant 25 balance, but in practice this does not succeed at all. Balancing requires generally a skillful operator and it is not quickly regulable, so that the crane must be nevertheless given to a relatively high stability, which means a considerable weight.

30 The object of the invention is a differential mechanism adapted to control the motor according to the actual momenta of load and counterweight, taking care of the own stability of the crane.

35 In carrying out the invention, the fixed end of the hoisting rope, or the top pulley, is anchored to a lever being to the said fixed end of the rope at the same angle as the jib is to the vertical, while the counterweight, or a part thereof, is slideable on another lever. The said 40 levers form the end links of a chain actuating the switches of the motor, so that the said switches are actuated by the differential action of the momenta of load and counterweight, and 45 control the motor in the sense of reestablishing the lost balance.

According to an embodiment of the invention a counterweight is provided, slideable on a rail at the side opposite to the jib and an auxiliary 50 counterweight is slideable on a rocking rail and trailed by the former one. A transmission mechanism connects the rocking rail and a bell crank lever adapted to compensate the inclination of the jib to a differential controller of a motor 55 driving the counterweight and of a battery car-

ried by the counterweight itself, such that at varying of load or position thereof the counterweight is automatically displaced, so as to carry out a perfect balance. Compensating means are provided for taking care of the weight of the transmission links, and may consist of springs or counterweights, or both together.

The crane according to the invention has many advantages upon the cranes hitherto known. The differential control mechanism for the 10 counterweight permits to utilize the weight of this part in the most useful manner, since the position of the counterweight may be made to correspond at any minute to the position and magnitude of the load. The automatic control 15 permits to save the expense of an operator, the differential action affords no lowering of the load for effecting regulation, the luffing of the jib does not call for any adjustment of the mechanism. Due to the compensating means, the mechanism 20 is perfectly balanced and of utmost sensibility.

The appended drawing illustrates diagrammatically a crane according to the invention, and precisely is:

Fig. 1 a lateral view of the crane, showing the 25 balancing mechanism.

Fig. 2 a plan of same,

Figs. 3 to 6 sectional views of the switching box,

Fig. 7 a particular thereof in an enlarged scale. 30

According to the Figs. 1 and 2, the crane consists of a fixed superstructure 1 carried by a turntable base 2 supported by the car and of a jib 3 pivoted in 4 on the superstructure 1 and supported by links 5 pivoted on a slide 82 carried by 35 the superstructure and operated by a luffing screw 83 driven by a motor 84, or in any other way. At the free end of the jib 3 a set of pulleys 6—60 is applied, carrying the hook or grip 7, and the hoisting rope 20, fixed at one end to a lever 21 40 and wound about the pulleys 6, 60, is secured to a hoisting drum 85 driven by a motor 86. At the other end of the crane a counterweight 8 is slideable, e. g. on rails 9 carried by the superstructure. These rails are provided with an indenture 87 45 meshing with a pinion 88 pivoted on the counterweight 8. The pinion 88 is driven through a connection 89 by an electric motor 90 located on the counterweight itself. Another small weight 10, trailed by the main counterweight 8, slides on 50 railtracks 11 pivoted in 12 on the superstructure and supported in 13, e. g. through links 14, by horizontal levers 15 fixed on a shaft 16 journalled on the superstructure of the crane and carrying also a lever 17 connected through a rod 18 with 55

the differential controller 19. The fixed or standing end of the hoisting rope 20 is fixed to the arm 21 of a bell-crank lever pivoted in 22 on the jib, whilst the other arm 23 of the said bell-crank lever is connected through links 24 to an amplifying lever 25 pivoted in 26 and connected through a rod 27 with arm 28 of a bell-crank lever situated at the lower end of the jib and pivoted thereon in 29. The other arm 30 of said lever acts 5 against a tube 31 coaxial with the luffing pivot 32 of the jib, journalled in 4 on the superstructure. The tube 31 acts on the other end against a lever 33 fixed on a shaft 34 carrying also another lever 35, which in turn is connected 10 through a rod 36 with the differential controller 19.

Arm 21 of bell-crank lever 21, 23 is made to be in its resting position parallel to the line connecting the pivot 4 of the jib and the axis of pulley 20, and the end of arm 21 is made to be almost coincident with the point of the periphery of pulley 60 where the rope 20 begins to wind itself thereupon, so that the rope 20 starts nearly vertically from arm 21. For the sake of clearness, on 25 the drawing the arm 21 has been drawn some considerable distance from this point, but it is intended that when hook 7 is in a position sufficiently far from pulley 60, the rope 20 is nearly vertical. However, generally speaking, the arm 30 21 of the said bell-crank lever could have any other position on the crane and any other inclination, provided that the angle between the rope 20 or the direction of effort exerted upon the said arm 21 and the arm itself be in any 35 case and at any position of the jib equal to the angle of inclination of the jib, that is to the angle comprised between the vertical and line connecting pivot 4 and the axis of pulley 60.

The differential controller 19 consists substantially of a shaft 40 rotatably mounted in bearings carried by a frame 41. On the shaft are fixed a plurality of contacting arms, whilst other arms are fixed thereto by means of elastic insets. A lever 42 transmits to the shaft the effort exerted 45 by the hoisting rope through the rod 36; another lever 43 transmits the effort exerted by the weight 10 through the rod 18. The ratio of the said levers is such that the said efforts compensate each other when the counterweight and the 50 load are perfectly balanced.

In order to effect the control of the motor driving the counterweight 8 and as a consequence also the weight 10, which is trailed by the former through the joint 37, two contacts 45, 46 are provided, one for each direction of travel, operated by the shaft 40 through contacting arms 47, 48 fixed thereto, at least one of them being provided with an elastic inset, such that the shaft may rotate even when the said arm has fully pushed 55 its contact.

The shaft 40 carries still another contacting arm, not shown, adapted to cut out the supply of current to the main circuit of the crane, when the momentum of the load is greater than that 60 of the counterweight by a predetermined amount. In such case all of the apparatuses stand still and lock themselves through their brakes, which are fitted with falling weights, so that no danger 65 may arise to the crane.

Since in this condition the differential controller 70 has the tendency to cut out the current as soon as the counterweight has reached its outmost position, whilst the crane has therein still a little stability, which it is desirable to utilize 75 fully, a spring 44 is provided, which is caught by

a lever 43 carried by the shaft 40 when it has accomplished the closure of the contact 46 for the outward motion of the counterweight. The spring 44 is intended to lock the rotation of the shaft 40, and as a consequence the cutting out 5 of the main circuit of the crane, until the momentum of the load has grown over that of the counterweight by an amount corresponding to the own stability of the crane.

The shaft 40 carries also, externally to the frame 41, an index, such that one may see at a distance what position the shaft is occupying; a handle carried by said shaft enables the operators to control by hand the movements of the counterweight and the main switch. A lock is 15 also provided, for locking said shaft 40 in each position, e. g. when one lets the crane be without survey, or when transporting it, in order to avoid the counterweight or any part of the crane to become unduly operative. 20

The embodiment of the differential controller or switching box illustrated in Figs. 3 to 7 consists of a case 38 provided with covers 39 and journalling the shaft 40. The shaft carries two operating cranks 51, 52, and two controlling 25 levers 53, 54, whilst a third controlling lever 55 is loose thereon and suitable elastic means are provided for recalling said lever 55 into a resting position.

According to an embodiment (Fig. 7) the lever 50 54 is fixed on the shaft 40 by means of a screw 56 and is provided with a resting surface 59. The lever 55 is loose on the shaft 40 and carries a projection 57 and a nose 58 facing the rest 59. A spring 56 is tended between projection 57 and 35 lever 54 and presses lever 55 with its nose 58 against rest 59. The pressure is such that the effort normally exerted upon the lever 55 for actuating the switch 69 is not sufficient for removing the contact surfaces 58 and 59 from one 40 another. In the embodiment of Fig. 6 the spring 51 is wound about the shaft 40 and the operating cranks 51, 52 are connected through links 61, 62 to two levers 63, 64 pivoted in 65, 66 and suitably connected with the rods 36 and 18. 45

A crank 71 fixed on the shaft 40 carries a pin 81 moving freely inside of a bracket 78, which in turn is kept by a spring 70 pressed against two rests 79, 80. When the shaft 40 rotates by an angle greater than a given angle, the pin 81 50 engages the bracket 78 and raises it from its rests 79, 80. Then the spring 70 exerts its braking action upon the shaft 40 and modifies the rating of the mechanism, such that a certain amount of overload is required on the hoisting rope for 55 effecting a further rotation of the shaft 40 and breakage of main circuit.

All of the pivots and journal bearings are suitably fitted with knives or ball races, in order to give to the mechanism a sufficient sensibility, 60 which should however not be excessive, since in this case the counterweight would not remain still a minute and could also give rise to dangerous oscillations of the crane. In such instance one would be obliged to fit a brake 77, suitably 65 located inside of the casing 38, and acting on the shaft 40.

The levers 53, 54, 55 each actuate a switch 67, 68, 69, of which the first is inserted in the main circuit of the battery, the second is connected such as to give rise to an inward motion and the last is connected such as to give rise to an outward motion of the counterweight. 70

The working of the device is as follows: when the load on the hook 7 increases, the mechanism 75

20 . . . 36 tends to make the shaft 40 to rotate in the sense of the arrows of Figs. 3 . . . 7, but as soon as the shaft 40 has rotated by a small amount, its lever 55 pushes the button of the switch 68 and establishes the contacts relative thereto. Then the motor of the counterweight starts up and the counterweight is driven astern until its momentum is equal to that of the load; then the spring of the switch 68 recalls the shaft 10 40 into the resting position, the circuits of the motor are cut out and the brake of the same locks itself, such that no further motion at all is possible.

When the load on hook 7 diminishes, the shaft 15 40 rotates in the opposite sense to that of the arrows, the lever 54 actuates the switch 68 and the circuit of the motor is closed such as to move the counterweight towards the centre of the crane. As soon as the momenta of load and 20 counterweight are equal, the spring of the switch 68 recalls the shaft 40 into its resting position, the circuits of the motor are cut out and the counterweight remains at rest.

Should the load to be hoisted or the arm there- 25 of be too great for the capacity of the crane, then the counterweight arrives at the end of its run without recalling the shaft 40 into its resting position. If the difference between the momenta of load and counterweight in this condition does 30 not exceed a predetermined value, corresponding to the momentum of own stability of the crane, then nothing else happens; but if this value is surpassed, then the shaft 40 is made to rotate further, against the action of springs 10 70 and 56 (or 75), of brake 11, of weights of the mechanism itself and counterweights 49, until lever 53 is pushed against switch 61, which cuts out the current and stops the hoisting motor, whereupon its brake locks it, keeping the load 40 suspended on the hook.

This device functions not only when the load to be raised exceeds the capacity of the crane, but also when the load increases very rapidly, for example, if a block of stone or iron is raised by steel ropes or chains, or if a load is raised from water into air, as is the case when rescuing sunken boats, cars, etc. In such cases the load increases so quickly that the counterweight has not the time necessary for reaching the new balancing position before the ropes or chains have stretched out, and the crane would be overthrown, did not the main switch cut out the hoisting motor.

The shaft 40 carries at one end an index 72, 55 suitably shaped as a crank and provided with a knob 13 and a locking means, e. g. a push-button 74. Said index serves for indicating to the operator the position occupied by the shaft 40, and thus the ratio of load and counterweight momenta, as well as the operation of various parts of crane. By means of the knob 73 the crank 72 may be operated by hand, thus executing by hand the operations normally accomplished automatically.

60 By turning said crank against the action of springs 70 and 56 (or 75) in the utmost position, corresponding to an overload, the main circuit of the battery is cut out and all of the parts of crane are set at rest. The button 74 permits then to 65 lock crank 72 in this position, thus avoiding any movement, either automatic or by hand. This is very useful when the crane should be abandoned or transported on any vehicle, to the purpose of avoiding an illicit use thereof.

75 The crane described and illustrated is intended

to be indicated merely as an example and many modifications and various embodiments are possible within the scope of the invention, in accordance with the appended claims. Thus the main switch may comprise only the circuits of some motors, for example, of the hoisting, luffing and sluing motors, or alternately the engine driving the counterweight may be fed directly by the source of current.

I am aware that prior to my invention portable 10 cranes have been made with counterweights dis- placeable so that their momentum varied in accordance with that of the load and also with counterweights slideable horizontally and such, wherein the counterweight is driven by electric 15 motors, eventually contained therein with the battery and other parts; and therefore I do not claim such a combination broadly, but I claim:

1. In a portable crane, comprising a hoisting rope, rails, a counterweight slideable along said 20 rails, a motor driving said counterweight and a differential controller for said motor, a mechanism connected with said hoisting rope and said counterweight and adapted to exert upon said differential controller efforts proportionate to the 25 momenta of the load on said hoisting rope and of the said counterweight.

2. In a portable crane having a jib adapted to be luffed, a hoisting rope, a counterweight, a motor driving said counterweight, and a differential 30 controller for said motor, a mechanism adapted to actuate said differential controller in connection with the momentum of the load on the said hoisting rope, and means adapted to compensate the effect of luffing of the jib on momentum of 35 load, so that the momentum of counterweight is in any case equal to the actual momentum of load, no matter how the intensity of the load and its distance from the center of gravity of the 40 crane vary.

3. In a portable crane having a jib adapted to be luffed, a hoisting rope fixed at one of its ends, a counterweight, a motor driving said counterweight and a controller for said motor, a mechanism adapted to actuate said controller in connection with the load on the said hoisting rope fixed at one of its ends, a bell crank lever pivoted on the said jib so that an arm of it is parallel to the jib and supports the fixed end of the said hoisting rope, whilst the other arm of said 50 lever is connected to the said mechanism.

4. In a portable crane having a hoisting rope, a jib adapted to be luffed, a counterweight, a link mechanism adapted to displace said counterweight in connection with the load on the said 55 hoisting rope and a luffing pivot carrying said jib, a tube surrounding said pivot and forming a link of said mechanism, adapted to transmit motion along the said mechanism independently of the luffing position of said jib.

5. In a portable crane comprising a hoisting rope adapted to carry a load and having a fixed end, rails, a counterweight, slideable along said rails, a motor adapted to drive said counterweight, a plurality of switches for said motor, a 65 differential mechanism connected with the fixed end of said hoisting rope adapted to actuate said switches so that the momentum of the counterweight be at any minute equal to that of the load on said hoisting rope, and a control member constituting a link of and actuated by said mechanism and adapted to operate said switches.

6. In a portable crane having a movable counterweight and an electric motor driving said counterweight, a set of switches adapted to energize

gize said motor for a direction of rotation corresponding to drive-out said counterweight, another set of switches adapted to energize said motor for driving-in said counterweight, for a 5 direction of rotation corresponding to driving-out said counterweight, another set of switches adapted to energize said motor for driving-in said counter-weight, a rocking shaft connected with load and counterweight and responsive to the difference 10 between the momenta of the load and of the counterweight, a lever moving with said rocking shaft and adapted to operate said first mentioned set of switches when the momentum of the load overcomes that of said counterweight 15 and another lever moving with said rocking shaft and adapted to operate said second mentioned set of switches when the momentum of said counterweight overcomes that of the load.

7. In a portable crane having a frame, a jib 20 pivoted on and forming a part of said frame and adapted to have various inclinations to the vertical, rails fixed to the frame, a hoisting rope suspended at one of its ends, a counterweight slideable along said fixed rails, a motor driving said counterweight, a controller for said motor, a lever pivoted on said jib and carrying the suspended end of said hoisting rope, the angle between said lever and said rope being at any moment equal to the inclination of the jib to the vertical, a 25 weight hauled by said counterweight, another lever pivoted on said frame along which runs said weight, and a differential mechanism operatively connected with both of said levers and adapted to actuate said controller in accordance with the resulting momentum which tends to upset the 30 crane.

8. In a portable crane comprising a frame, a jib pivoted on said frame and having an angle of inclination to the vertical, a hoisting rope, 40 rails pivoted on said frame, a counterweight movable along said rails, a motor driving said counterweight, and a controller for said motor; a differential member operating said controller, a lever fulcrumed on the crane, means connecting 45 said hoisting rope and said lever, and adapted to exert upon said lever a force proportionate to the stress in the hoisting rope and at an angle equal to said angle of inclination of the jib, means connecting said lever and said differential member, 50 and means connecting said rails and said differential member.

9. In a portable crane having a frame, a jib pivotally mounted on said frame, a hoisting rope adapted to carry a load, rails, a counterweight

movable along said rails, a motor driving said counterweight, a group of switches for said motor, a shaft adapted to actuate said switches, and means connecting said shaft, said counterweight and said rope, adapted to exert on said shaft a momentum proportionate to the difference between the momentum of said counterweight and that of the load; a bracket, an abutment carried by said crane, a spring adapted to press said bracket against said abutment, and a pin carried by said shaft and adapted to loosely engage said bracket.

10. In a portable crane having a hoisting rope, an electric motor for winding said rope, a movable counterweight, a motor driving said counter- 15 weight, switches for said second mentioned motor, a main switch and a shaft operating said switches and said main switch; a crank keyed on said shaft, a pin carried by said crank and a locking knob on said pin, adapted to lock said shaft in the position in which said main switch is opened.

11. In a portable crane having a hoisting rope adapted to carry a load, a plurality of mechanisms for causing movements of the load, multiple electric motors to drive the mechanisms that cause the aforesaid movements, rails, a counterweight running on said rails, another electric motor driving the said counterweight, a set of switches adapted to energize the said last mentioned motor 30 for a direction of rotation corresponding to driving-out of the counterweight, another set of switches adapted to energize the same last mentioned motor for driving-in of the counterweight, a rocking shaft connected with the load on the said hoisting rope and the counterweight, and responsive to the difference between the momenta of the load and of the counterweight, a lever moving with the said rocking shaft and adapted to operate with the first mentioned set of switches when 40 the momentum of the load overcomes that of the counterweight, another lever moving with the said rocking shaft and adapted to operate the said second mentioned set of switches when the momentum of the counterweight overcomes that of the load, a general switch inserted in the feed circuit of all the motors and a third lever moving with the said rocking shaft and capable of opening the general switch when the equilibrium of the crane is compromised by the load in spite 45 of the maximum shifting outside of the counterweight.

MARIO MOLINELLI.
